UNITED STATES PATENT OFFICE.

CHARLES A. HARRIS, OF COAL VALLEY, AND GEORGE K. ROUSH, OF MCKEESPORT, PENNSYLVANIA.

ADVERTISING SIGN.

Application filed November 7, 1927. Serial No. 231,736.

Our present invention has reference to an advertising sign of a type designed to attract attention to a particular class of goods sold or handled by a merchant, repairman or the like.

A further object is the provision of a sign which will attract attention to a store or repair shop even when a party is unable to read the characters or letters of the sign.

10 A further object is the provision of a sign that shall be effectively supported upon the front of a store, repair shop or the like and which in turn effectively supports thereon a transparent body formed to portray the 15 class of goods sold or repaired in the store and in which provision is made for illuminating the transparent body so that the same will be amply displayed in the night time, and further wherein the rays of light from 20 the body will be also directed onto the sign.

A still further object is the provision of an electrically illuminated sign in which an illuminated body is formed to portray the class of goods sold or repaired and in which 25 the wires for the bulbs in the body are concealed in the frame or support of the sign.

To the attainment of the above broadly stated objects and various others which will appear as the nature of the invention is 30 better understood, the invention resides in the construction, combination and operative association of parts, one of a number of satisfactory embodiments of which is illustrated by the accompanying drawings.

35 In the drawings:

Figure 1 is a side elevation of an advertising sign in accordance with this invention.

Figure 2 is a top plan view thereof.

Figure 3 is an approximately sectional view on the line 3—3 of Figure 1.

Figure 4 is a plan view looking toward the main support of the sign.

Figure 5 is an approximately central longitudinal sectional view through the transparent body of the improvement to illustrate the manner in which the lamp bulbs are arranged therein.

Figure 6 is a transverse sectional view approximately on the line 6—6 of Figure 4.

50 Figure 7 is a detail transverse sectional view approximately on the line 7—7 of Figure 4.

Our novel and improved advertising sign is designed to be fixedly supported on the

front of a store or repair shop to which the sign is to direct attention. The sign includes a horizontal support 1 which, in the main, is formed from a single strip of angle iron. This support 1 is centrally rounded upon itself so that the horizontal flange 2 thereof will be extended inwardly, and the vertical flange 3 will be projected upwardly. The rounded portion is continued rearwardly and the arms thereof are spaced away from each other to provide a widened portion. In the showing of the drawings, this widened portion is shaped to correspond with the shape of the toe, outer portion of the sole and the heel of a shoe, the sign in the present instance, being of a type to be employed by dealers in shoes or by shoe repairers. From the rear or heel portion of the body, the arms thereof are continued rearwardly in parallelism, as indicated by the numerals 70

4. The arms 5 merge into oppositely directed ear portions 6, the said ears being flattened and being provided with openings for the reception of securing elements that enter the front 7 of the store or repair shop. The parallel arms 5, at the rear portions thereof provided with the ears 6, and the portions thereof at the juncture of the widened outer part of the support are connected together and reinforced by plates 8. Also the rear or heel of the widened outer portion of the support has passed therethrough a bolt or rod 9 whose ends are rounded upon themselves to provide eyes 10 and to each of these eyes there is secured a guy or supporting rope or cable 11. These cables have their free ends secured to eyes 12 formed on the outer faces of plates 13 that are fixed to the front 7 of the store or repair shop to the opposite sides and above the ears 6.

The support above described has secured thereto and is braced by a frame. The frame is also of metal, the outer member 14 of which being fixed to the central or toe portion of the widened end of the support, and the upper horizontal element 15 of the frame being fixed to the front 7 and being rounded toward and secured between or directly to the parallel arms 5 of the support. The lower horizontal member 16 of the frame has an inner angle extension 17 directed toward and secured to the parallel portions 5 of the support. Between the

upper and lower horizontal elements of the frame there is a vertical connecting member or plate 18. The outer portion of this frame has secured therein a suitable sign 19.

Designed to rest on the horizontal flanges provided on the outer and widened portion of the support there is the sole and heel portions of a hollow transparent body 20. The body in the showing of the drawings is in the form of a shoe. The toe portion of this shoe is passed through an arched strap 21 whose ends are secured to the sides of the widened portion of the body. This strap is provided with a plurality of apertures 22.

Arising from the support, at the juncture of the widened outer portion and the parallel arms 5 thereof, there is a tubular standard 23. This standard, on its upper end, is formed or otherwise provided with what I will term a flanged cap 24 that is arranged over the top of the body 1. Passing through the flange of the cap member 24 there are headed threaded elements 25, and these elements are received between outstanding flanges 26 on the upper portion of the hollow and transparent body 20.

The top of the cap member 24 has secured upon its lower face a disc 27 which is received in the open top portion of the transparent body 20 and which snugly contacts with the inner wall thereof. The disc has a centrally depending part 28 in which is screwed the base of a lamp bulb 29.

Fixed in the top of the toe portion of the hollow transparent body 20 there is a clip or bracket 30 that engages with the base portion of a second bulb 31. The wires from both of the bulbs are suitably encased, the wires from the bulb 31 being directed along the base and bottom and the rear portion of the hollow body 20 and from thence being directed to the tubular standard 23 between the parallel arms 5 of the support, while the encased wires for the bulb 29 pass through a suitable opening in the disc 27 and are also directed through the tubular support 23 and between the parallel arms 5 of the support. Of course, the wires pass through an opening in the wall 20 and are connected to suitable plugs which are screwed in wall sockets.

From the foregoing description when read in connection with the accompanying drawings, it will be seen that we have provided a sign which will effectively attract attention to the particular class of goods sold in a store or the particular class of goods repaired in the store or shop. The support is braced in a manner that will sustain the same in a horizontal position and will prevent its displacement or dislodgment regardless of weather conditions. The cap 24 effectively protects the interior of the hollow transparent body 20, and as previously stated, the frame for the sign 19 reinforces the support. When illuminated the bulbs

will direct the rays of light through the transparent body in all directions, certain of such light rays from the bulb 31 passing from the apertures in the strap 21, the cap obscuring the upward direction of the rays from the bulb 29. The rays of light from both of the bulbs will pass through the widened or spread outer portion of the support on which the transparent body rests so that the sign 19 will have both of its sides or faces illuminated.

While the advertising sign herein described is well suited for the purpose set forth, it is not intended to limit the invention to such details of construction or arrangement of parts, as we hold ourselves entitled to make all such changes therefrom as fairly fall within the scope of what we claim.

Having described the invention, what we claim is:

1. A sign designed to be supported on the front of a store or the like, comprising, in combination, a horizontal member having its inner end fixed and its outer portion spread apart to widen the same, said member having an outer continuous upstanding flange, a transverse apertured strap having its ends secured to the forward portion of the member, a transparent body resting on the spread portion of the member engaged by the strap, and said flange, means at the rear of the spread portion of the member engaging the top of the transparent body and closing the same and means for illuminating the transparent body.

2. A sign designed to be supported on the front of a store or the like, comprising, in combination, a horizontal member having its inner end fixed and its outer portion spread apart to widen the same, said member having an outer continuous upstanding flange, a transverse apertured strap having its ends secured to the forward portion of the member, a transparent body resting on the spread portion of the member engaged by the strap and said flange, means at the rear of the spread portion of the member engaging the top of the transparent body and closing the same, means for illuminating the transparent body, a truss frame centrally beneath and bracing the member and a sign carried by the truss frame.

3. A sign for the purpose set forth, comprising a support which includes, an angle iron centrally rounded upon itself having its sides continued rearwardly in spaced relation and from thence brought partly together and extended in parallelism, ears on the last mentioned arms of the members for the reception of securing elements, spacing means between the parallel arms of the member, an apertured strap having its ends secured to the outer and spread portion of the member, a transparent body

formed to portray a class of goods having its base portion received in the spread portion of the angle member and engaged by the strap, angularly arranged guy ropes also supporting the member, a hollow upstanding standard on the member having an angularly arranged flanged cap to be received over the open top of the transparent body, adjustable means passing through the flange 10 of the cap and contacting with the body, a truss frame depending from and secured

centrally to the member, said truss frame designed to support a sign, lamp bulbs in the hollow body having their conductors directed through the cap and through the 15 hollow standard between the closely related parallel arms of the angle member.

In testimony whereof we affix our signatures

CHARLES A. HARRIS.
GEORGE K. ROUSH.
